EXPANSIBLE WRIST WATCH BRACELET

Roland F. Boehm, Short Hills, N. J., assignor to
 Gemex Company, Union, N. J., a corporation
 of New Jersey

Application July 27, 1953, Serial No. 26,154

Term of patent 7 years

(Cl. D45—4)

To all whom it may concern:

Be it known that I, Roland F. Boehm, a citizen of the United States and a resident of Short Hills, Essex County, New Jersey, have invented a new, original, and ornamental Design for Expansible Wrist Watch Bracelet, of which the following is a specification, reference being had to the accompanying drawing, forming part hereof, in which:

Fig. 1 is a top plan view of an expansible wrist watch bracelet showing my new design;

Fig. 2 is a bottom plan view thereof;

Fig. 3 is an edge view thereof;

Fig. 4 is a fragmentary top plan view of the central portion thereof shown in an expanded condition;

Fig. 5 is a side elevational view of one of the top links thereof taken along the line 5—5 of Fig. 1;

Fig. 6 is a side elevational view of one of the top links thereof taken along the line 6—6 of Fig. 1;

Fig. 7 is a side elevational view of one of the top links thereof taken along the line 7—7 of Fig. 1;

Fig. 8 is a side elevational view of one of the top links thereof taken along the line 8—8 of Fig. 1;

Fig. 9 is a perspective view of one of the central top links thereof; and

Fig. 10 is a perspective view of the top link shown in Fig. 5.

I claim:

The ornamental design for an expansible wrist watch bracelet, substantially as shown and described.

ROLAND F. BOEHM.
